UNITED STATES PATENT OFFICE.

LUTHAN W. HAMMOND, OF VENICE, NEW YORK.

NECK-YOKE COUPLING.

1,159,020.

Specification of Letters Patent.

Patented Nov. 2, 1915.

Application filed March 14, 1914. Serial No. 824,818.

To all whom it may concern:

Be it known that I, LUTHAN W. HAMMOND, a citizen of the United States, and a resident of Venice, in the county of Cayuga and State of New York, have invented a certain new and useful Neck-Yoke Coupling, of which the following is a specification.

This invention relates to harnesses and has for its object a neck yoke coupling whereby the individual jockey neck yokes can be readily detached from the yoke on the pole; and it consists in the combinations and constructions hereinafter set forth and claimed.

In describing this invention, reference is had to the accompanying drawings, in which like characters designate corresponding parts in all the views.

Figure 1 is a fragmentary view of a jockey neck yoke embodying my invention. Fig. 2 is an elevation looking upwardly in Fig. 1, the members of the coupling being shown as separated to permit the detachment of the ring which is attached to the yoke on the pole. Figs. 3 and 4 are elevations of one of the coupling members, taken at a right angle to each other.

1 designates the bar or tree of a neck yoke, as a jockey neck yoke, the opposite ends of which are connected to the backers of the harness in any well known manner.

2 designates the members of the coupling by means of which a ring 3 is attachable to, and detachable from, the jockey neck yoke, this ring being the ring carried at each end of the yoke connected to the pole of the vehicle.

One of the members 2 is shiftable relatively to the other to separate portions thereof to permit the ring to be attached and detached. Preferably the members 2 are duplicates of each other and include hubs 4 which are mounted on the intermediate part of the neck yoke bar or tree 1, and outwardly extending arms having their ends 5 arranged to come together to form a split eye to receive the ring. As here shown, the ends 5 are bent toward each other and meet or lap to form the split eye for receiving the ring, the split of the eye being located entirely on the side of the eye opposed to the yoke bar and extending transversely through said side whereby the ring hooked into the eye can be removed from the eye upon the opening of the latter without unhooking movement toward the yoke bar. One of the

members 2 is fixed to the tree 1 and the other is movable about the tree 1 to separate and bring together the lapping portions 5 and open and close the eye. The lapping portions are complementary and made to interfit, as clearly seen in Figs. 2, 3 and 4. The lapping portions of the arm 5 extend substantially parallel to the axis of the hubs 4, and each lapping portion terminates short of the major part of the other arm, which major part extends substantially radially from the hub. Hence the eye can be opened wide to permit the detachment or attachment of the coupling ring of the neck upon a small movement of the movable member 2. Thus the coupling ring can be radially detached without any manipulation.

The fixed member is secured to the bar or tree 1 in any suitable manner as by nails 75 driven through holes therein, and for economy in manufacturing, these members are duplicates of each other and interchangeable, and the holes are in the form of notches 6 formed in the edges of the hub 4. The notches 6 in the shiftable member 2 perform no function.

The shiftable member is held from movement in its normal position by suitable locking means, and as here shown this locking means includes a key in the form of a strap 7 riveted at one end at 8 to the bar or tree 1 and extended through transverse holes as loops 9 provided on the hubs 4 on the opposite side thereof to that on which the arms 2 are located, the strap being secured at its other end to the bar 1, by means of a button 10. The loops 9 are normally in alignment, but upon the unfastening of the strap at 10 and the withdrawal of the same to the right Fig. 1 out of the loops 9, the shiftable member 2 can be moved about the bar 1 to separate the lapping portions 5 to permit the insertion or the removal of the ring 3, and after the ring has been inserted the movable part 2 may be again moved about its axis to close the split eye and the key replaced in its normal position.

This invention is particularly advantageous in that the coupling members 2 are particularly simple in construction, economical in manufacture, easily operated and easily replaced if broken.

What I claim is:

1. A neck yoke comprising a yoke bar and a coupling for attaching a ring to the yoke bar comprising two members, each having a

hub mounted on the yoke bar and an arm projecting from the hub, the arms forming a split eye and one of the members being movable about the yoke bar to open and close the eye, the split of the eye being located entirely on the side of the eye opposed to the yoke bar and extending transversely through said side whereby the ring hooked into the eye can be removed from the eye upon the opening of the latter without unhooking movement toward the yoke bar, substantially as and for the purpose described.

2. A neck yoke comprising a yoke bar and a coupling for attaching a ring to the yoke comprising two members, each having a hub mounted on the yoke bar and an arm projecting from the hub and formed with a laterally extending end portion which laps the laterally extending end portion of the arm of the other hub, the arms being spaced apart at the hubs and the laterally extending lapsing portions of the arms being opposed to the yoke bar so that said arms with their laterally extending portions and the yoke bar inclose an eye located close to the hubs and the yoke bar and the laterally extending lapsing portion of each arm terminating short of the major part of the other arm whereby upon the separation of the arms a short distance, a maximum opening

is provided through which the ring may pass, and means for locking the members from movement about the yoke bar and thereby holding the lapsing portions of the arms in engagement, substantially as and for the purpose described.

3. A neck yoke comprising a yoke bar, and a coupling for attaching a ring to the yoke comprising two members having hubs mounted on the bar, and arms projecting outwardly from the hubs and having their extremities arranged to engage each other and form a split eye, one member being movable about the bar for separating said arms, the members having loops projecting from their hubs and normally arranged in alignment, and a key for passing through the loops for holding the shiftable member in its normal position, substantially as and for the purpose described.

In testimony whereof, I have hereunto signed my name in the presence of two attesting witnesses, at Venice Center in the county of Cayuga, in the State of New York, this 27th day of Feb., 1914.

LUTHAN W. HAMMOND.
